UNITED STATES PATENT OFFICE

2,506,659

ELECTRON DISCHARGE TUBE

Georges Bezy, Paris, France, assignor to Compagnie Generale de Telegraphie Sans Fil, a corporation of France

Application May 14, 1947, Serial No. 747,962
In France April 11, 1941

Section 1, Public Law 690, August 8, 1946
Patent expires April 11, 1961

9 Claims. (Cl. 250—158)

1

This invention relates to electron discharge tubes and more particularly to tubes of the kind utilizing an electrode or an assembly of electrodes employed to act as a mirror reflecting the whole or part of a stream of electrons or charged particles in the tube.

The invention is illustrated in and explained in connection with the accompanying drawing in which:

Figure 1 is a theoretical diagram showing arrangements heretofore known for purposes of showing the differentiation therefrom of my invention; Fig. 2a is a diagrammatic illustration showing in side view one embodiment of my invention; Fig. 2b is a diagrammatic illustration in front view of the embodiment of my invention shown in Fig. 2a; Fig. 3 is a theoretical and diagrammatic view showing the application of my invention to cylindrical, circular or parabolic reflector electrodes; and Fig. 4 illustrates in diagrammatic arrangement the application of my invention to an indirectly heated cathode system associated with a positive anode for accelerating the electrons.

Referring to Figure 1 which shows a typical known arrangement for reflecting electrons or charged particles 1, the reflector consists of a spherical, parabolic, or other cup or as shown of a planar electrode A. This electrode which is maintained at an electron retarding potential with respect to another electrode B, sets up at some position which is dependent on the geometry of the electrodes and on the voltages applied thereto, an equipotential surface XX', from which electrons emitted, for example, by an electron gun C are reflected. This surface which is planar in Fig. 1 though it might for example be spherical if the electrode A were spherical constitutes a mirror of fixed focal length and given radius.

The invention provides a reflector arrangement comprising essentially a simple electrode, that is planar, which is easy to construct, but which may be arranged to present the qualities of a mirror of any desired shape and which will permit any desired particular focal length to be obtained by control by electrical means.

Fig. 2a shows diagrammatically in side view and Fig. 2b in front view one embodiment of the invention. The references employed in Figs. 2a and 2b correspond to those in Fig. 1.

In Fig 2 electrode B is as before positive in relation to the electron gun C and accelerates the electrons towards the reflector electrode A which, as shown consists of a plurality of parts, in the

2

form of concentric rings, strips or wires, 1, 2, 3, 4, 5 which are electrically insulated from one another and are maintained at different desired potentials lower than that of electrode B, by a potentiometer P. By varying the voltages V₁, V₂, V₃, V₄, V₅ applied to the parts 1, 2, 3, 4, 5 it is possible to make the equipotential surface produced of almost any desired shape so that it may constitute a convex or concave mirror or (if all the voltages are equal) a planar mirror. With applied voltages as indicated in Fig. 2a the mirror is concave, the voltages being successively decreasing outwardly of the central part 5.

The invention is equally applicable to cylindrical, circular, parabolic or reflector electrodes. Fig. 3 represents, for example, a cylindro-parabolic electrode A constituted by insulated parallel wires or strips 1, 2, 3, 4, 5 adapted to be polarized from taps on a potentiometer P.

Mirrors in accordance with this invention can be utilized to reflect plane pencils obtained by suitable electron concentration arrangements associated with the cathode.

A similar arrangement can also be applied to concentrate the discharge from a cathode. In Fig. 4, for example, C is an indirectly heated cathode and B a positive anode for accelerating the electrons. Around the cathode is an electrode A composed of several insulated pieces 1, 2, 3 and so on circularly surrounding the cathode and maintained at voltages such that the electrons emitted from C are concentrated on the center of the anode B.

The invention obviously enables manufacturing errors in electrode construction to be compensated for in use by applying suitable electrical correction potentials to the parts of the reflector electrode.

The invention is especially applicable to very short wave generator tubes, of the kind in which part of a velocity modulated electron current is caused to return towards the cathode. However, the invention is also of general application, for example, to electron multipliers, oscilloscopes and the like.

Modulation of the return or reflected pencil of electrons can, if desired, be produced by introducing a modulation voltage at the terminals of the potentiometer P which feeds the different parts constituting the reflector electrode.

What I claim is:

1. Electric discharge apparatus comprising a source of charged particles, an electrode connected with a potential accelerating these particles, a flat electrode connected with a potential

3

which is negative in relation to the preceding electrode for the purpose of producing between these two electrodes an equipotential surface reflecting the particles, and means associated with the said flat electrode for varying the form of the said equipotential surface.

2. Electric discharge apparatus comprising a source of charged particles, an electrode connected with a potential accelerating these particles, a flat electrode divided into a plurality of insulated portions, and means for applying to these portions variable potentials which are negative in relation to the first of the above-mentioned electrodes, for the purpose of varying the form of the equipotential particles reflecting surface 15 produced between the two electrodes.

3. Electric discharge apparatus comprising a source of charged particles, an electrode connected with a potential accelerating these particles, a flat electrode divided into a plurality of insulated concentric rings, and means for applying to the different rings potentials which are negative in relation to the first of the above-mentioned electrodes, these potentials being gradually variable toward the center of the flat electrode for the purpose of obtaining between the two electrodes a curved equipotential surface for the reflection of the particles.

4. Electric discharge apparatus comprising a source of charged particles, an electrode connected with a potential accelerating these particles, a flat electrode divided into a plurality of insulated parallel bands, and means for applying to the different bands potentials which are negative in relation to the first of the above-mentioned electrodes, these potentials being gradually variable toward the center of the flat electrode for the purpose of obtaining between the two electrodes a curved equipotential surface for the reflection of the particles.

5. Electric discharge apparatus comprising a source of charged particles, an electrode permeable to these particles and connected with a positive potential in relation to the source, a flat electrode disposed on the trajectory of the particles after their passage through the permeable electrode and connected with a negative potential in relation to this permeable electrode for the purpose of producing between these two electrodes an equipotential surface for the reflection of the particles, and means associated with the said flat electrode for varying the form of the said equipotential surface.

6. Electric discharge apparatus comprising a source of charged particles, an electrode connected with a potential accelerating these particles, a flat electrode disposed in the vicinity of the source and connected with a negative poten-

tial in relation to the preceding electrode for the purpose of producing between these two electrodes an equipotential surface for the reflection of the particles emitted by the source toward the said accelerating electrode, and means associated with the said flat electrode for varying the form of the said equipotential surface.

7. Electric discharge apparatus comprising a source of charged particles, an electrode connected with a potential accelerating these particles, a flat electrode connected with a negative potential in relation to the preceding electrode for the purpose of producing between these two electrodes an equipotential surface reflecting the particles, means associated with the said flat electrode for varying the form of the said equipotential surface, and means superposed to the said form-varying means for imparting a modulation to the flow of particles.

8. Electric discharge apparatus comprising a source of charged particles, an electrode connected with a potential accelerating these particles, a flat electrode divided into a plurality of insulated portions, and means for applying to these portions individual potentials which are negative in relation to the first of the above-mentioned electrodes, for the purpose of giving a predetermined form to the equipotential surface of reflection of the particles produced between the two electrodes.

9. Electric discharge apparatus comprising a source of charged particles, an electrode connected with a potential accelerating these particles, a flat electrode divided into a plurality of insulated portions, means for applying to these portions individual potentials which are negative in relation to the first of the above-mentioned electrodes, for the purpose of giving a predetermined form to the equipotential surface of reflection of the particles produced between the two electrodes, and means for applying to these portions potentials variable at the rhythm of modulation for the purpose of modulating the flow of particles reflected by the equipotential surface.

GEORGES BEZY.
